R. ZOHM,
FLY SWATTER,
APPLICATION FILED OCT. 17, 1921.

Patented Aug. 15, 1922.

UNITED STATES PATENT OFFICE.

RICHARD ZOHM, OF ROCKFORD, ILLINOIS.

FLY SWATTER.

1,425,622.

Specification of Letters Patent. Patented Aug. 15, 1922.

Application filed October 17, 1921. Serial No. 503,270.

To all whom it may concern:

Be it known that I, RICHARD ZOHM, a citizen of the United States, residing at Rockford, in the county of Winnebago and 5 State of Illinois, have invented certain new and useful Improvements in Fly Swatters, of which the following is a specification.

This invention pertaining to fly swatters has for its principal object to provide a 10 swatter of generally improved construction characterized by its novel means for holding the wire fabric body in flat condition. This means includes the use of a pair of flat spring members associated with the handle 15 and pressed against opposite sides of the wire fabric body and acting as a yieldable reinforcing and stiffening means.

Another object is to provide in a fly swatter, a flat spring element forming part of 20 the handle and having spring cross bars upon and between which the wire fabric is stretched and secured. This gives a substantial but flexible support for the wire fabric body.

25 Another object is to provide a fly swatter so constructed that it may be produced at a comparatively low cost and will be practical and durable for the purposes intended.

Other objects and attendant advantages 30 will be appreciated by those familiar with this art as the invention becomes better understood by reference to the following description when considered in connection with the accompanying drawings, in 35 which—

Figure 1 is a side view of a fly swatter embodying my invention;

Fig. 2 is a view of the wire fabric body and immediate means for supporting it; and 40 Figs. 3 and 4 are enlarged sections on the lines 3—3 and 4—4 respectively, of Fig. 1.

My invention contemplates the provision of novel means for supporting the wire fabric body 5 in such manner that it will be 45 held in flat condition, will not readily pull away from its supporting means, and will be sufficiently light and flexible as to be well suited for the purposes of a fly or insect swatter of the character in mind. The 50 top and bottom edges of said fabric body are turned over and clamped upon narrow cross bars 6 and 7, respectively, of spring material. These bars are secured medially between their ends to a main spring member 55 8 which constitutes part of the handle and reaches substantially throughout the length

thereof. As shown in Fig. 3, the upper end of the member 8 is turned over and clamped onto the upper cross bar 6. The cross bars may be welded, soldered or otherwise suitably secured to the main spring member 8. A fabric binder 9 envelopes the entire marginal edge of the wire fabric body and is 60 sewed onto the latter.

The projecting end 10 of the member 8 65 forming the handle is reinforced and stiffened by a pair of sheet metal pieces 11 and 12, U-shape in cross section, clamped onto the member 10, as shown in Fig. 4. This handle structure or reinforcing may, however, be of any suitable or preferred construction. In the present instance, the members 11 and 12 serve to clamp and hold in 70 position a pair of flat spring elements 13 and 14. These elements, confined at one end 75 between the handle members 10 and 11, are slightly bowed intermediate their ends as shown in Fig. 3. It follows that the upper ends 15 of these spring elements will be urged against the wire fabric body, thereby 80 holding the latter against the spring member 8.

By reason of the foregoing construction, the wire fabric body will be very securely supported without danger of easily pulling 85 away from its supporting elements. Furthermore, this support is flexible along the members 6, 7 and 8 and the spring elements 13 and 14 tend to maintain the wire fabric body in flat condition. Consequently when 90 in striking a flat surface, the swatter body engages the surface at an angle and the force of the blow together with the tendency of the various spring elements will cause the body to bear flat against the surface substantially throughout its area and thus 95 crush an insect or fly at any point within said area. It will be manifest, therefore, that the function of such spring elements in maintaining the swatter body in flat condition, yet flexible, is an important factor in 100 the effective use of a device of this kind.

It is believed that the foregoing conveys a clear understanding of the object prefaced above, and while I have illustrated a single 105 working embodiment, it should be understood that various changes might be made in details of construction without departing from the spirit and scope of the invention as expressed in the appended claims.

I claim:

1. A swatter of the character described

comprising a rectangular wire fabric body, a main spring member, one end of which constitutes part of a handle structure and to the other end of which is secured a pair 5 of spring cross bars in longitudinally spaced relation, the opposite ends of said wire fabric body being turned over said cross bars, and a binder enveloping the turned over ends of the fabric body.

10 2. A swatter of the character described comprising a rectangular wire fabric body, a main spring member, one end of which constitutes part of a handle structure and to the other end of which is secured a pair 15 of spring cross bars in longitudinally spaced relation, the opposite ends of said wire fabric body being turned over said cross bars, a binder enveloping the turned over ends of

the fabric body, a handle structure secured to said handle end of said main spring member, and spring elements secured to said handle structure and pressing against opposite sides of the wire fabric body at a medial point thereon. 20

3. A swatter of the character described comprising a strip of flat spring material equipped at longitudinally spaced points with spring cross bars, a handle secured to one end of said flat spring member, a wire fabric body having opposed ends turned over and clamped onto said spring cross bars, and flat spring elements associated with the handle and pressed against opposite sides of the wire fabric body. 25

RICHARD ZOHM. 30
